WIRE STRETCHER

Ernest G. Geisendorff, Bellville, Tex.

Application June 24, 1947, Serial No. 756,745

3 Claims. (Cl. 24—132)

1

This invention relates to improvements in wire stretchers and more particularly to a wire gripping device which will firmly grip a wire strand and may be pulled toward a post or other anchorage to stretch the wire.

It is among the objects of the invention to provide an improved wire gripping device of simplified construction to which a wire strand can be easily secured and which will automatically grip the wire with a force proportional to the pull on the wire during the stretching operation, which device will not kink the wire or produce sharp bends which might weaken or crack the wire, which will not scratch or break the galvanizing coating or other finish of the wire, which will grip barbed, twisted or smooth wire with equal facility, and which is economical to manufacture, durable in use and easy to operate.

Other objects and advantages will become apparent from the consideration of the following description in conjunction with the accompanying drawing, wherein:

Figure 1 is a top plan view of a wire gripping device illustrative of the invention.

Figure 2 is a side elevation of the wire gripping device illustrated in Figure 1.

With continued reference to the drawing, the wire gripping device comprises a frame, generally indicated at 10, made up of a pair of longitudinal, angle-iron leg members 11 and 12 substantially parallel to each other and spaced apart to provide between them a central opening 13. The leg members 11 and 12 are connected together at corresponding ends by a transverse end member 14 of angle cross-section which is welded or otherwise permanently secured at its ends to the corresponding ends of the leg members 11 and 12. The leg members 11 and 12 are secured to the member 14 in a manner such that upstanding flanges 15 of the two leg members are disposed one at each side of the central opening 13 and extend outwardly from the frame in the same direction. These flanges are gradually tapered or uniformly reduced in width in a direction away from the transverse end member 14, as is clearly shown in Figure 2, to facilitate the insertion of a wire through the central opening 13 between the leg members of the frame.

A U-shaped eye or pull loop 16 is secured to the end of the frame opposite the end member 14 by having its end portions welded or otherwise permanently secured respectively, to the end portions of the legs 11 and 12 of the frame.

A rectangular abutment block 17, preferably formed of hard wood, is secured within the angle

2

of the end member 14 by suitable fastening means such as the bolts or screws 18, the outwardly extending flange 19 of the end member overlying the side of the block 17 at the extreme end of the frame.

An arm 20 of angle cross-section has one side superimposed upon the side of the leg 11 which is attached to the end member 14 and is pivotally connected to the frame at one end by a suitable pivotal connection such as the corresponding bolt 18 which secures the abutment block to the frame. The free end of the arm 20 is movable about the pivotal connection 18 toward and away from the leg 11 and the arm has its other side extending past the outer edge of the leg 11 in a direction opposite the direction in which the leg flanges or sides 15 extend. This other or depending side 21 of the arm is provided with an elongated, longitudinal slot 22 and a roller shaft 23 extends through this slot so that one end portion thereof extends transversely across the frame 10 when the arm 20 is in the closed position illustrated in Figure 1, while the opposite end portion of the shaft extends outwardly from the arm 20 to provide a handle.

A roller 24 is journaled on the end portion of the shaft 23 which extends transversely of the frame 10 and is secured against movement lengthwise of the shaft by suitable abutment washers 25 surrounding the shaft 23 one at each end of the roller 24. The abutment washer at the end of the shaft may be held in place by a head 26 formed on the end of the shaft and the washer intermediate the shaft length may be secured in place by a pin 27 extending through a transverse aperture in the shaft 23. The roller 24 is provided with a flat side 28 which operatively engages the adjacent surfaces of the frame legs 11 and 12 to resist rotation of the roller upon the shaft 23 when a wire is gripped in the wire stretcher.

In operation, the arm 20 is first swung outwardly so that the roller 24 is moved to a position in which it is entirely clear of the central opening 13 of the frame 10. A wire strand 30 is then laid in the central opening and forced downwardly between the flanges or sides 15 of the frame legs and the arm 20 is then closed with the leg 11 bringing the roller between the frame legs and the wire strand and to a position in which it extends transversely across the frame, as illustrated in Figure 1. The wire is then bent around the roller to provide a roller-engaging loop and a pull is applied to the pull-loop 16. The roller will be then moved longitudinally of the

frame legs compressing one side of the wire loop between itself and the abutment block 11. During this movement of the roller it will be rotated until the flat side 28 comes into engagement with the adjacent surface of the frame legs whereupon further rotation of the roller will be resisted and the roller will be bodily moved toward the abutment block. As a pull is placed on the pull-loop 16 the roller 24 will be forced toward the abutment block compressing the wire strand loop with a force proportional to the force of the pull on the pull-loop. When the wire has been properly stretched it may be released from the stretcher by bending the wire to release the loop surrounding the roller 24, moving the free end of the arm 23 away from the associated frame leg to withdraw the roller from the loop and then removing the frame from the wire lying in the central frame opening.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A wire stretcher comprising a frame having a pair of substantially parallel, spaced apart, angle iron legs arranged with upstanding flanges at opposite sides of the intervening space, an angle iron end member secured transversely to said legs at corresponding ends thereof with one side of said end member directed away from said legs, said upstanding sides of said legs decreasing uniformly in width in a direction away from said transverse end member to facilitate the insertion of wire into said stretcher, a pull loop connecting the ends of said legs opposite said transverse end member, a hard wood abutment block secured in the angle of said transverse end member, an arm of angle shaped cross-section pivotally connected at one end to one of said frame legs adjacent said end member and having a longitudinally slotted side extending past said one frame leg to the side thereof opposite the corresponding upstanding sides of said legs, a roller shaft extending

through said slotted side of said arm, and a roller on the end of said shaft extending across said frame legs to receive a loop of wire brought over said end member between said legs, and grip said wire between itself and said abutment block, said roller having a flattened side engageable with the adjacent surfaces of said legs to resist rotation of said roller and thereby facilitate gripping of said wire between said roller and said block.

- 10 2. A wire stretcher, comprising a narrow, elongated, U-shaped frame, having a pair of substantially spaced apart legs, a pull loop connected to the legs of said frame at the open end of said frame, an abutment block secured to said frame at the closed end thereof, an arm pivotally secured at one end to the closed end of said frame for movement of its free end toward and away from one edge of said frame and having a longitudinally slotted portion extending along said one edge of said frame, a roller shaft extending through said slotted arm side and having one end portion adapted to be positioned transversely of said frame, and a roller on said one end portion of said shaft operative to receive a loop of wire brought between said frame legs and grip said wire between itself and said abutment block.
- 15 3. A wire stretcher, comprising a rectangular frame having a central wire receiving opening closed at one end and a pull loop at the opposite end, an abutment block secured to said frame at the closed end of said opening, an arm pivotally connected at one end to said one end of said frame and having a longitudinally slotted side, a roller shaft extending through said slotted arm side and having one end portion adapted to be positioned transversely of said frame, and a roller on said one end portion of said shaft cooperating with said abutment block to grip a wire between itself and said block so that the wire may be stretched by a pull on said pull loop.
